Specification for Design.

Patented Aug. 30, 1921.

Application filed March 27, 1920. Serial No. 369,446. Term of patent 14 years.

To all whom it may concern:

Be it known that I, GASPARO COSTANTINO, a subject of the King of Italy, residing at Niagara Falls, in the Province of Ontario and Dominion of Canada, have invented a new, original, and ornamental Design for a Cobbler's Tool, of which the following is a specification, reference being had to the accompanying drawing, forming a part thereof.

The figure is a perspective view of a tool, showing my new design.

I claim:

The ornamental design for a cobbler's tool as shown.

GASPARO COSTANTINO.
